UNITED STATES PATENT OFFICE.

RICHARD W. STEVENS, OF ALTON, ILLINOIS.

BACK-BAND BUCKLE AND CHAIN-SUPPORTER.

SPECIFICATION forming part of Letters Patent No. 341,516, dated May 11, 1886.

Application filed July 16, 1885. Serial No. 171,792. (No model.)

To all whom it may concern:

Be it known that I, RICHARD W. STEVENS, of the city of Alton, county of Madison, in the State of Illinois, have invented a certain 5 new and useful Improvement in Trace Supporters and Buckles, of which the following is a full, clear, and exact description, reference being had to the accompanying drawings, forming part of this specification.

10 My invention relates to a trace supporter and buckle; and my invention consists in features of novelty hereinafter fully described, and pointed out in the claims. This is an article that may be made of cast or wrought metal, and which may be applied to a back-band or other strap without being stitched thereto, but which may be made fast to the strap by stitching or by riveting, if desired.

15 Figures 1, 2, and 3 are perspective views showing the article in various positions. Figs. 20 4, 5, and 6 are perspective views showing its application to a strap or band woven from cotton or other material. Figs. 7, 8, and 9 are perspective views showing it applied to a 25 leather strap or band. Fig. 10 is a side view of the article, showing it used as a buckle.

30 A is a closed frame or ring having in its side bars sockets a , for the ends of the pintle-bar b of the tongue-piece B. The frame A has two bows, a' and a'' , the former, a' , being shown 35 of general rectangular form, the other, a'' , being bent at a' , forming a recess, in which the tongue C rests when used in conjunction with this bow. The tongue has an ogee bend, c c' , so that when used in conjunction with the bow 40 a' the bow rests in the recess c' .

In Figs. 7, 8, and 9 a trace-chain, E, is shown 45 engaged upon the tongue C and resting on the bow a' or a'' , as the case may be. The strap 50 or band D in this case is understood to be a back-band. It will be seen that the trace-chain can be very readily attached or detached, as a loop or bend of the chain may be dropped through the bow and one of the links engaged 55 upon the tongue. On the other hand, to disengage the trace from the tongue it is only needed to draw out the bow from contact with the tongue, when the link will drop off the end of the tongue. Although it is so easy to dis- 60 50 engage the trace-chain when desired, there is absolutely no possibility of an accidental dis-

engagement, as the weight of the chain outside the bar or the strain upon it in use will evidently prevent such disengagement. The tongue C forms part of the piece B, and the 55 bow b' also forms part of the same, so that when the tongue is engaged in the strap, band, or web the bow b' is tightly pressed against the same. The transverse bar of the bow a' has upon the part that bears against 60 the strap or band corrugations, as shown at a' , so as to take hold of the strap, and the transverse bar of the bow b' has like corrugations, b'' , on the part bearing against the strap, band, or web for a like purpose, the corrugations of 65 the bow a' being upon the inner side, and those of the bow b' upon the outer side.

In Figs. 1, 5, and 8 the bows a' and b' are in contact with each other, and the tongue in conjunction with the bow a' . In the arrangement 70 shown in Figs. 5 and 8 the strap is simply passed through the two bows a' and b' and bar a' and the tongue passed through the strap, so that a considerable part of the strain comes upon the tongue and upon the part of the strap 75 in connection with it.

In Figs. 4, 6, and 7 the strap is shown 80 "ogee'd" around the two bows b' and a' or a'' , as the case may be, the former being shown in Fig. 4 and the latter in Figs. 6 and 7. In these cases the ogee bend takes a considerable part of the strain, and thus relieves the tongue and the part of the strap bearing upon it.

In Fig. 2 the frames A and B are shown at 85 right angles to each other, to exhibit the construction with more clearness.

In Fig. 3 the parts are shown in the position shown also in Figs. 6 and 7, but without the strap or chain.

In Fig. 9 the bow a' is shown attached to 90 the band or strap D by a leather or metal loop, F, folded around the bow and riveted to the strap. As a modification of this, the loop may be cast upon the bow. As the bow b' is in the same piece with the tongue C, it will be seen 95 that the bearing of the strap on the tongue will force the bow hard against the leather and pinch it between the bows b' and a' when the leather passes between them, as shown in Fig. 4, or between the bows b' and a'' , as in Figs. 6 100 and 7, the corrugations of the bow b' in both cases and in conjunction with those of bow a' in

Fig. 4, aiding the hold of the bows on the strap.

In Fig. 10 one end of a strap, D, is secured to the bow b' , and the other end passed through 5 the bows $a^2 a'$ and engaged upon the tongue. The bend c of the tongue allows the trace-chain to run straight past the attachment when the tongue acts in conjunction with the bow a' , while when the bow a^2 is used in 10 conjunction with the tongue the bend a^1 of the bow allows the chain to extend through the supporter in a straight line, thus causing no strain on the parts.

I claim—

15 1. The trace-supporter consisting of an outer frame, A, and an inner frame, B, formed with a pintle-bar, b , at one side, by which it is hinged to the outer frame, a bow, b' , projecting from one side of the pintle-bar, and a 20 tongue extending from the other side of the latter, substantially as set forth.

2. The combination of the closed frame or

ring A, having its bow a' , with corrugations, and a frame, B, pivoted thereto, composed of a pintle-bar, b , bow b' , and tongue C, made in 25 one piece.

3. The combination of a closed frame, A, with corrugations a^3 , and frame B, composed of bar b , bow b' , having corrugations b^2 , and the tongue C, all parts of the frame B being 30 fixed together by casting or otherwise.

4. The combination of outer frame or ring, A, with interior frame turning therein and composed of a pintle-bar, b , a bow, b' , and a tongue, C, bent outward at c , for the purpose set forth. 35

5. The combination of the frame or ring A, having a bend, a^4 , therein, and a frame, B, turning in the frame A, and having a bow, b' , and a bent tongue, C, substantially as and for the purpose set forth.

RICHARD W. STEVENS.
